SPEAKER ENCLOSURE

Robert W. Becker, Naperville, and Melvin H. Boldt, Glenview, Ill., assignors to Zenith Radio Corporation, Chicago, Ill.

Filed Apr. 27, 1973, Ser. No. 354,963

Term of patent 7 years

Int. Cl. D14—01; D31

U.S. Cl. D26—14 G

FIG. 1

FIG. 4

FIG. 3

FIG. 2

FIG. 1 is a perspective view of our design for a speaker enclosure showing the front, top and left side thereof;

FIG. 2 is a front elevational view thereof;

FIG. 3 is a top view thereof; and

FIG. 4 is a right side elevational view of the speaker enclosure.

The bottom and left and right sides are substantially plain and unornamental.

We claim:

The ornamental design for a speaker enclosure, substantially as shown and described.
